UNITED STATES PATENT OFFICE.

FREDERICK C. STAUFFEN, OF BALTIMORE, MARYLAND, ASSIGNOR TO UNION SHIP-BUILDING COMPANY, A CORPORATION OF PENNSYLVANIA.

HAULING-OUT SYSTEM FOR SCRAPPING VESSELS AND APPARATUS FOR THE SAME.

Application filed March 4, 1924. Serial No. 696,865.

To all whom it may concern:

Be it known that I, FREDERICK C. STAUFFEN, a citizen of the United States, and a resident of Baltimore city, in the State of Maryland, have invented a new and Improved Hauling-Out System for Scrapping Vessels and Apparatus for the Same, of which the following is a specification.

The object of my invention is an improved system of cutting up vessels' hulls, especially that part ordinarily below the water line.

A further object of my invention is an improved system of hauling a vessel.

15 A further object of my invention is the providing an apparatus upon which my improved system may be practiced.

A further object of my invention is the providing a simple, substantial and cheap 20 method of hauling bodies out of the water.

A further object of my invention is an improved railway for hauling vessels.

With the foregoing and other objects in view, my invention consists of the methods 25 employed, combination and arrangements of systems, apparatus and means as herein-after specifically provided and illustrated in the accompanying drawings wherein is shown the preferred embodiment of my invention, but it is understood that changes, 30 variations and modifications may be resorted to which come within the scope of the claims hereunto appended.

Fig. 1 is a plan view of my improved 35 railway adapted for hauling a vessel under my improved system of wrecking, and shows a vessel's bow on the same. Fig. 2 is a cross-section in elevation taken through 2—2 of Fig. 1, and Fig. 3 is an enlarged view of 40 one set of rails and the roller operating thereon, and Fig. 4 shows an inverted section, drop weight and recoil absorber.

Similar numerals refer to similar parts throughout the several views.

45 1 is a rail. I have found an ordinary T railroad rail of a hundred pound per yard weight sufficient for hauling of vessels of several thousand tons. 2 is a separator spacing rails 1 apart a desired pre-determined 50 amount and through which securing bolts 3 pass, which bolts secure rails 1 together. Rails 1 are supported upon timber sub-structure 4, which structure rests on concrete foundation, piles or other proper support;

rails 1 being spiked in the usual way or 55 held by some suitable means. I have found a screw spike very desirable. In the rail above mentioned $\frac{1}{8}$ by 7 inches long. Screw spikes are used.

On rails 1 operates operating roller 5, the 60 middle portion of which is enlarged as is shown at 6, and chamfered or curved to more nearly fit the average bilge of vessels intended to be hauled thereon. The ends of the roller 5 are provided with flanged element 7 which assists in directing and keeping the roller in line. Through the roller is a pin 8 which secures spacers 9, which spacers are held in pre-determined relative position by spacer separator and bolt 70 through the same 10.

I have found in practice that rolls adapted to haul a vessel as above described function properly when the enlarged portion thereof on a center line is 9 inches; the roller 5, 75 being $4\frac{1}{2}$ inches diameter, and the rollers spaced about 1 ft. apart along the spacer.

At the head of the railway I provide a hoisting or winding apparatus 11, in the instance described, of over a hundred tons 80 deadweight lifting capacity, this operating to haul the vessel by means of blocks 12 and 13.

The general construction of the railway 85 resembles somewhat the ordinary construction in that the rails extend beneath the water to a sufficient depth to float the floating body 14 on to the rollers, the ordinary cradle being eliminated. The hull after being hauled out is cut up into sections 90 convenient for handling when to be loaded into gondola cars, say 40 feet long, and of desirable width. These sections are then lifted by crane 15 and laid over on the ground inverted, one of these sections being shown 95 as 16, and a heavy weight 17 is lifted by the crane and dropped on to the inverted section 16 by releasing the trip-hook 18 the falling weight jars and cracks and practically cleans the interior of the section of 100 all cement or concrete held therein.

The trip-hook 18 is of special construction to permit of easily releasing a weight, in the case described of some three tons. This hook consists of hook proper 19, hook-keeper 20 and trip-dog 21. 22 is a recoil absorber.

The operation of my process and inven-

tion is as follows: The floating body 14 is floated over the rollers located near the end of the railway or rails and the hauling mechanism or block 13 is secured to the same by means of a suitable chain or cable of desired length, which is secured to the hull just above the water line of the then flotation by burning holes, or otherwise, and securing to the stem. The vessel is then 10 hauled out travelling about three times as fast as the rollers, using the dimensions of rollers above suggested; sufficient rollers and spacers being provided to accommodate the vessel to be hauled. The forward portion 15 of the vessel being sharp bears more strongly on the inside edge of the curved roller when coming in contact with the rollers, while the flat, or bilge portion, bears more strongly on the outside edge after 20 the vessel becomes fully grounded on the rollers. After the vessel is hauled out she is cut up and treated as described above by

any well known means, such as an acetylene torch.

Having thus described my invention, 25 what I claim and desire to secure by Letters Patent is—

1. An apparatus for drawing floating bodies out of the water, consisting of an inclined way, tracks thereon, and a series 30 of connected and spaced rollers traveling thereon upon which rollers the floating body directly rests, and upon which it travels.

2. An apparatus for drawing floating bodies out of the water, consisting of an 35 inclined way, tracks thereon, a series of differential rollers the smaller diameters of which roll on said track and upon the larger diameter of which the said body is rolled.

FREDERICK C. STAUFFEN.
